BED DIVAN

Samuel L. Grossman, Los Angeles, Calif.

Application February 10, 1943, Serial No. 475,396

2 Claims. (Cl. 5—47)

This invention relates to bed divans, and has among its salient objects to provide improvements which will make possible a simple, practical and economical bed divan without the use of metal parts, other than nails, and which need not be pulled out from the wall in order to open it up from a divan to a bed.

Another object of my invention is to provide a construction and arrangement in which a two-part bed portion can be pulled out on the base structure for bed purposes, the parts being so hinged together that they can be let down for bed purposes, or one part can be interlocked to the other part in such a way that it can be moved to raise said other part up to an angular position to form the back portion of a divan.

Another object of my invention is to provide a construction and arrangement whereby the movable two-part bed portion (forming seat and back as a divan) can be easily released so as to be lifted as a unit from the supporting base, thus making it possible for this two-part portion to be manufactured at one place, if desired, and the supporting base be manufactured at another place.

Other objects and advantages will appear from the following more detailed description of one practical embodiment of the invention, taken in connection with the accompanying sheet of drawings.

In the drawing, Figure 1 is a plan view, looking down upon a bed divan embodying my invention, let down in bed form, with a portion of the fabric covering torn away to disclose the arrangement of the working parts;

Figure 2 is a sectional view taken on line 2—2 of Fig. 1;

Figure 3 is a similar view on the same line 2—2, with the one part of the bed raised up and interlocked to the other part;

Figure 4 is a similar view showing how the interlocked parts are rocked down to raise the rearward part up to angular position as the back of the divan, with the front part down as the seat;

Figure 5 is a sectional view taken on the line 5—5 on Fig. 1, showing the hinge arrangement of the two-part bed portion, with the stops, when the same is pulled out and let down for bed purposes;

Figure 6 is a similar view, on the same line 5—5, with the parts moved back into divan position;

Figure 7 is a sectional view taken on line 7—7 of Fig. 1 to show certain details in connection

with the hinge pin, which is movable lengthwise, out of a slot in the end structure;

Figure 8 is a vertical sectional view on the line 8—8, on Fig. 1, with the bed portions down, but only showing the end member in which is a slot for the movement of the hinge pin of the two-part bed portion.

Figures 9 and 10 are details taken on lines 9—9 and 10—10, Fig. 1.

Referring now in detail to the drawing, my divan, or bed divan, includes a box, or frame-like base of rectangular form, made of the members 9, 9, with upright end portions, 10, 10. Inner frame members, as 11, 11, are shown on the inside of the box frame members 9, 9, and these members form supports and slide-ways for the two-part bed-divan structure. It will be understood, of course, that these end portions can be covered or upholstered in any desirable manner. I have shown them plain, as the covering is no part of the invention.

The two-part bed-divan structure, shown down in bed form in Figs. 1, 2 and 5, consists of a front frame 12, and a rear frame 13, with a connecting member, as 14, on the inner side and secured firmly to the front frame 12, with a hinge pin 15 inserted through said connecting member and through a portion of the rear frame, at each end, as at 15', Figs. 5 and 6. Slide retaining members, as 16, are secured to the inner side of the end members 12, and extend down on the base members 11, as seen in Figs. 1, 2, 5, 6.

I will now describe the mechanism shown for interlocking the two parts 12 and 13 together for the purpose of raising one by the other.

Transversely across the middle portion of the front frame 12, are two spaced slide-way members, 17, 17, having grooves on their inner or adjacent faces, in which a slide member 18 is shown, with a handle 19 on its outer end, and a stop 20 on its middle portion. A slot 21 is shown in the rearward member of the frame 12, through which the end of the slide member 18 can pass, as seen in Figs. 1, 2 and 9, in particular.

Mounted on the rearward member 13, in its middle portion, as seen in Figs. 1, 2, 3 and 4, is an interlocking block 22, secured to a middle brace member 23, with a second brace member 24 between the member 13 and member 23. The interlocking block member 22 is beveled on its front face and is adapted to be engaged by the end of the slide member 18, as it is moved through the slot 21, in the rear member of the front frame 12, as seen in Figs. 3 and 4, where the members 55 are shown in interlocked positions.

With the parts in the positions shown in Figs. 1, 2 and 3, the front frame 12 is raised up by hand to the angle shown in Fig. 3, whereupon the slide member 18 can be moved through the slot 21, with its end moving on to the beveled face of the block 22, as seen in Fig. 3, where it interlocks with said block 22. Now if said frame 12 is pulled down to the position shown in Fig. 4, the rear or back portion 13 is raised to the position shown in Fig. 4.

A rest block, as 25 is shown on the rearward part of the base frame members 11, at each end with its upper end slightly beveled, and said divan back portion 13 is provided at each end with a cooperating block, as 26, to move upon the upper end of said rest block 25, when the parts are in the positions shown in Figs. 4 and 6, to give more rigidity.

In the end portions, 10, 10, is a horizontal member 27, as seen in Fig. 8, in which is a slot 28, and in which the hinge pins 15 move as the two-part members 12 and 13 are drawn forward and moved back. When the hinge pins 15 at each end are pushed inwardly so as to clear the outer end members, 27, as seen in Figs. 7 and 8, and without disconnecting the members 12 and 13, said members 12 and 13 can be lifted as unit up out of the base frame. This makes it possible for said two-part members 12 and 13, to be constructed separately, in a standardized form and easily put into place on the base structure, between the end portions 10, 10, thereof.

Other brace or strengthening members, such as 12' and 13', can be used as may be required. It will be understood, of course, that the structures as here shown are made of wood and are nailed together, although any means of fastening the parts together can be used.

It will be seen that the entire structure can be set back against a wall and does not have to be pulled out in order to change from divan, as seen in Fig. 4, to bed form, as seen in Figs. 1 and 2.

When changing from divan form, Fig. 4, to bed form, it is only necessary to pull the parts out to the position indicated in Fig. 2, raise the parts to the position shown in Fig. 3, raise the interlocking slide member 18 to free it from the interlocking block 22, and then let the front part down to the horizontal position.

To make up in divan form, it is only necessary to raise the front part up to the position shown in Fig. 3, push the slide member 18 down to the position seen in said Fig. 3, and then pull the front member down to the low position, as seen in Fig. 4, and push both parts back to the back position shown in said Fig. 4.

Thus I have provided a very simple, practical and economical combination bed and divan which can all be made of wood and which will answer every purpose. Underneath there is room for bedding and mattresses, as may be needed to make a comfortable bed.

I do not limit my invention to the details of construction and arrangement shown for explanatory purposes, except as I may be limited by the hereto appended claims.

I claim:

1. In a bed divan: a supporting structure having end portions, two frame structures upon said supporting structure, between said ends, connecting members at the ends of said two frame structures hingedly connecting them together, the hinge pins thereof releasably and slidably connecting said connecting members with the ends of said supporting structure, whereby said frame structures can be moved forwardly and rearwardly, or removed, as a unit, a locking member slidably mounted on one of said frame structures and movable into locking engagement with the other of said frame structures, means on the other of said frame structures to receive said locking member when moved to locking position after said frame structures are moved to an angle relative to each other, whereby said frame structures are locked together at an angle to form seat and back as a divan, said locking member being releasable to permit said frame structures to be moved to horizontal bed forming positions.

2. In a bed divan, a supporting structure having end portions, two frame structures upon said supporting structure to lay flatwise thereon to project forwardly and rearwardly between said end portions, connecting members pivotally connecting said two frame structures together at their opposite ends and including pivot pins slidably connecting said frame structures with the opposite ends of said supporting structure, said pivot pins being releasable to disconnect the two frame structures from said supporting structure, interlocking means between said two frame structures for interlocking them in angular positions when one of said frame structures is raised to form the back of a divan, said frame structures being slidably forwardly and rearwardly on said supporting structure between said end portions, and releasable at the opposite ends from the end portions of the supporting structure to be lifted bodily from said supporting structure, substantially as shown and described.

SAMUEL L. GROSSMAN.
